UNITED STATES PATENT OFFICE.

ANDREAN G. RONNING AND ADOLPH RONNING, OF MINNEAPOLIS, MINNESOTA.

ROAD GRADER.

Application filed July 18, 1924. Serial No. 726,662.

This invention relates to grading machines and the primary object is to provide a grader and a frame mounting therefor which renders it particularly adaptable for use in connection with tractors of the well known Fordson type. A further object is to provide means of a novel character for controlling the position, angle and movement of the grader implement. A further object is to provide novel and practical means adapted to be actuated by the power unit of the tractor for affecting the grader adjustments and for steering the entire machine. A still further object is to provide means automatically actuatable by the fluctuating ground wheels or roller rearward of the grader blade for adjusting the working position of the grader as it advances over the road. A still further object is to provide a container for surfacing material and means for distributing or spreading such material either in advance or rearwardly of the grader implement. These and a number of other objects are affected by the novel, ingenious and practical construction and arrangement of parts which will now be described and claimed, and which are all clearly and distinctly illustrated in the accompanying drawings, which form a part of this specification, and in which:

Fig. 1 is a side elevation of a complete machine embodying the principles of our invention, a portion of the container being broken away and some parts being omitted.

Fig. 2 is a rear view of the machine as shown in Fig. 1.

Fig. 3 is a front elevation of the front end of the machine.

Fig. 4 is a side elevation similar to Fig. 1, but showing certain modifications thereover.

Fig. 5 is a top or plan view of the machine as shown in Fig. 4.

Fig. 6 is a side elevation of a preferred construction, showing certain further modifications in the machine, and with end portions thereof broken away.

Fig. 7 is a rear view of the machine shown in Fig. 6.

Fig. 8 is an enlarged detail sectional view as on the line 8—8 in Fig. 5.

Fig. 9 is an enlarged fractional detail view of a certain driving connection which will later be described in detail.

Fig. 10 is an enlarged detail section on the line 10—10 in Fig. 6.

Fig. 11 is a plan view of the grader de-

vices proper, as seen about as on the line 11—11 in Fig. 6.

Fig. 12 is an enlarged detail plan view, showing the shaft 163 (with a central portion broken out), and the drive connections at its opposite ends, as seen when looking down upon these parts as shown in Figs. 6 and 7.

Referring to the drawings more particularly and by reference characters A designates a tractor unit of the Fordson type, to which is secured and from which rearwardly extends an auxiliary frame B, a yoke C at the front end of the machine being substituted for the normal fore carriage or steering truck D of the tractor, so as to support the front end of the tractor when the fore carriage has been removed. The construction of the frame B, its application to the tractor A, and the method of operating the new machine which is thus formed, is illustrated and described in our co-pending application Serial No. 717,511, which was filed on June 3rd, 1924. In that case the structure illustrated is confined to one in which the front truck D of the tractor is removed and applied to the rear end of the auxiliary frame. This we have also shown in the present case, as in Figs. 6 and 7, but in Figs. 1, 2 and 4, the normal steering truck of the tractor is not utilized for any purpose, and the rear end of the frame B is supported by a roller carriage E, which is more suited to a road working machine under certain circumstances.

The construction and steering operation of the truck D, as shown in Figs. 6 and 7, may be briefly described as follows: The truck or carriage D consists of an axle 141 to the ends of which are secured, by the customary spindle members D¹, the steering wheels D², which are simultaneously angled or turned by a connecting rod which is not here shown, but is shown as at 21 in our above mentioned co-pending application and is similar to the well known connecting rods such as are used in automobiles. One of the spindle members has an arm D³, actuated by the usual steering gear connecting rod D⁴. When the truck D is in its original position on the tractor the socket D⁵ at the upper end of the rod D⁴ connects with the crank D⁶ (Fig. 6), or one similar to it, controlled by the hand wheel 33. When the truck D is used in the new arrangement, however, the rod D⁴ is extended forwardly,

and is actuated by the crank D⁶ through the medium of an extension rod D⁷, which is slidably secured to the frame B by brackets D⁸, and a connecting rod D⁹. The character 5 D¹⁰ designates the usual radius rod of the axle 141 and connects the axle with a frame member D¹¹. As the axle is pivoted, as at D¹², to the depending bolster D¹³ of the frame B, it will be seen that it may tilt, in 10 the usual manner in a transverse plane, with respect to the machine, but will be held against rotation in a horizontal plane. It will also be noted that it is also a simple matter to steer the wheels D² by connecting 15 them up with the normal steering apparatus of the tractor, with the aid of the mechanism we have just described.

Referring now to Figs. 1 and 2 of the drawings, the numeral 15 designates a yoke or frame in the arms of which are journaled the ends of a shaft 16, which carries a drum or roller 17. The yoke 15 is pivotally secured, for transverse tilting movement, by a pivot 18, to a casting 19, which is journaled to rotate on a vertical center from the frame B, and which is provided with a worm gear 20 adapted to be actuated or rotated by a worm 21, on a shaft 22. This shaft 22 has a bevel pinion 23 which meshes with a 25 similar pinion 24 on a vertical shaft 25, which, with a hand wheel 26, forms the steering column. This steering column is arranged adjacent to a seat or support 27, near the rear end of the frame, so that the 30 operator at this point may steer and control the machine and all its parts.

It may here be stated that the machines shown in Figs. 1, 2, 4 and 5 are provided with dual controls so that the entire machine 40 may be controlled either from the tractor seat 28 or by an operator sitting in the rear seat 27. In the manually steered device shown in Figs. 1 and 2, the steering can also be affected from the front or tractor 45 seat by means of a cable 29 which is wound around a sheave 30 on the shaft 25, passes around an idler pulley 31, and is then wound around a spool 32 which is rotated by the normal tractor steering hand wheel 33.

50 In the manually controlled but power steered device shown in Figs. 4, 5 and 8 the worm ring gear 20 is rotated by a worm 34 on a shaft 35, which is provided with a friction wheel 36 adapted to frictionally engage 55 a disc 37 or a disc 38, depending upon the direction of rotation desired. The position of the wheel 36 is determined by a bell crank yoke 39 which is controlled either from the front steering column 40, by a rod 41, or 60 from the rear steering column 42 by a rod 43. The two discs 37, 38 are secured on a shaft 44 which is continuously rotated by the power shaft 45 of the engine through the medium of bevel pinions 46, shaft 47, a 65 worm 48 and a worm gear 49.

The continuously rotated shaft 44 also carries a small frictional wheel 50, which is slidably keyed to it, and which continuously engages a disc 51 on an inclined shaft 52, the frictional resistance between the two 70 wheels being adjustable by a lock nut device 53. The wheel 50 is movable to or to either side of the dead center of the disc 51, by a forked member 54, controlled by a hand lever 55, through a rod 56. The shaft 75 52, by means of bevel pinions 57, rotates a shaft 58, of an endless carrier 59, the upper run of which is arranged to move in either direction over the floor 60 of a container 61. Thus material within the container may be 80 gradually fed out of either end thereof, by motive power, so that it may be delivered either forwardly or rearwardly of the grader, as may be desired, and as has already been set forth in the above mentioned 85 application Ser. No. 717,511.

The driving connection between the power shaft 45 of the engine and the carrier 59, as shown in Figs. 1 and 2 is somewhat simplified, and consists of a pair of pinion driven shafts 62 and 63, the latter of which has a friction roller 64 which is adjustably engageable with a disc 65, on the shaft 58, by a fork 66 on a rod 67. This rod 67 is slidable in bearings 68. At its front end it connects with a hand lever 69, so that it can be regulated from the front seat 28, and it may also be regulated from the rear seat 27, by a lever 70, through a shaft 71 and an operating finger 72.

The usual clutch lever 73 and the gear shifting lever 74 of the tractor may also be controlled from the rear seat 27 by extension devices which are shown in Fig. 1, and will now be described. The clutch lever 73, which is pivoted as at 75 is depressed by the foot of the operator (sitting in the seat 28) before the speed lever 74 may be shifted. It is connected by a cable 76 to the arm 77 of the shaft having 110 a foot pedal 79 so that when the pedal 79 is depressed by an operator in the seat 27 it will release the clutch the same as when the front lever 73 is pressed down. The lever 74 is also controlled from the rear seat by a slidably journaled shaft 80 having a hand lever 81 at its rear end for turning and sliding the shaft. The front end of the shaft 80 has a finger 82 which universally engages a bracket 83, secured on the lever 115 74; so that by operating the hand lever 81 the lever 74 may be shifted either transversely or forth and back, to affect the desired gear shift.

The construction and operating connections of the grader, which is suspended under the frame B and rearwardly of the tractor unit, will now be described.

Referring for the moment to Figs. 1, 2 and 4, 5, it will be seen that the grader 130

frame consists of two rearwardly diverging angle iron draw bars 84, connected at their front ends by a casting 85, which is pivotally secured as at 86 to the main tractor unit. The rear ends of the draw bars 84 are secured to a transverse beam 87. Secured under the frame 84, 87, and rotatably adjustable with respect thereto, is a circular supporting member 88, known as a circle, and under it is secured, by brackets 89 and braces 90, the scraper blade 91. The ends of the beam 87 are suspended by link hooks 92, 93 from the arms 94, 95 at the rear ends of shafts 96, 97, respectively. The front ends of the shafts 96, 97 are provided with worm pinions 98 which mesh with worms 99, which in turn are actuated by hand wheels 100. Thus either or both ends of the beam 87 may be manually raised and lowered, as desired, by actuating the hand wheels 100.

In the machine shown in Figs. 4, 5 and 8 the scraper frame is provided with a lifting or adjusting mechanism, which although manually controlled (from either seat 27 or 28) is power operated by the engine, as follows: The ends of the beam 87 are connected by links 101 and 102 to cranks 103 and 104 on respective shafts 105 and 106. The shaft 106 has a worm gear 107, meshing with a worm 108 on a shaft 109. The lower end of the shaft 109 has a friction roller 110 which is arranged between to engage either of the discs 37 or 38. The roller is moved into engagement with either of the discs, as desired, by a bell crank member 111 which, in turn, is actuated by a link 112 and an arm 113 of a sleeve 114 which is journaled to the frame B. This sleeve is also provided with arms 115 and 116, the first of which is connected by a rod 117 to a rear (left) foot pedal 118, while the latter is connected by a rod 119 to a front (left) foot pedal 120.

Rotatably secured in the sleeve 114 and also journaled to the frame B, as at 121, is a shaft 122 having three crank arms 123, 124 and 125. The crank arm 123 is connected by a link rod 126 to a front (right) foot pedal 127, the arm 125 is connected by a link rod 128 to a rear (right) foot pedal 129, and the arm 124 is connected by a link 130 to a bell crank lever 131, which controls the position of a friction roller 132, of a shaft 133, with respect to its engagement with either of the two friction discs 134 and 135 on the continuously rotated shaft 44. The upper end of the shaft 133 drives a worm gear 136 on the shaft 105, to raise and lower the right end of the beam 87, as may be required. It will thus be obvious that the operation of the mechanism for controlling the vertical position of the right end of the scraper beam 87, by the action of either pedal 127 or 129, will be sub-

stantially the same as the raising and lowering of the left end of the beam by the pedal 120 or 118.

The entire scraper frame may also be raised and lowered without changing the working angle of the blade 91 by clutch hand levers 137 and 138, which, by means of respective clutch locks 139 and 140, lock the pedals 120, 127 and 118, 129 together for simultaneous movement. These clutches are both shown as out of active engagement in Fig. 5.

In Figs. 6 and 7 is shown a scraper adjusting mechanism which is controllable both by hand and also automatically by the tilted position of the truck D which rides over the road surface which has already been worked by the scraper or other road working implement. Thus the angle of the scraper blade will be automatically adjusted to correspond to the angle or inclination of the axle 141, and as the truck or carriage D does not roll over bumps or hollows in the road surface, as do the traction wheels, its axle will have a substantially uniform angle at all times. This mechanism also co-operates with but does not in any way interfere with the manual adjusting mechanism for tilting the blade, as may be desired under various circumstances. The mechanism referred to consists of a pair of shafts 142 and 143 having respective cranks 144 and 145 at their rear ends and keyed worm gears 146 and 147 at their front ends. The cranks 144 and 145 are connected by links 148 and 149 to the axle 141. Trunnioned upon the shafts 142, 143, and retained between the gears 146, 147 and bearing members 150, are a pair of bell crank levers having substantially horizontal arms 151 and 152, connected by links 105 or link hooks 153 and 154 to the ends of the beam 87. The upstanding or normally vertical arms 155 and 156 of these bell crank levers are bifurcated, as shown, and in them are journaled shafts 157 and 158, having worms 159 and 160 which mesh with the gears 146 and 147. Bevel pinions 161 and 162 operatively connect the shafts 157, 158, to shafts 163 and 164, the latter two having universal joints 165 and being driven or actuated by suitable hand wheels 166 and 167, through the medium of bevel pinions 163^A. It may here be noted that the front end of the shaft 163 (and also 174) is journaled and supported in a bearing extension 163^B of a bracket 163^C, and that the rear part of the shaft is journaled and supported in a bearing extension 155^A of the member 155.

In the operation of the mechanism immediately above described, it will be seen that when the right end (for instance) of the axle 141 moves upwardly it will raise the crank 144 and cause all the parts 146, 159, 155, 155^A, 157, 161, 163 and 151 to rotate on the 130

axis of the shaft 142, thus raising the arm 151 and link 153 to correspondingly adjust or raise the right end of the beam 87 and scraper blade 91. The same movement will also obviously lower the left end of the blade, with a result that the working edge of the blade will always bear the same corresponding position to the angle of the axle 141. Should it now be desired to either raise or lower the entire blade or to increase or decrease its inclination, that result may be affected by operating either one or both of the hand wheels 166 or 167. Thus, for instance, if the wheel 166 is rotated, it will correspondingly operate through the shaft 163 and pinions 161 to rotate the worm 159 and cause it to crawl or move on the rigid gear 146, thus causing the yoke arms 155 and 151 to turn on the shaft 142 and raise the link 153 of the scraper frame bar 87. As the shaft 163 is provided with suitable universal joints 165 it will not interfere or bind when the worm 159, and its bearings, move in an arc over the worm gear 146.

25 The scraper or surfacing mechanism proper, as shown in Figs. 6, 7, 10 and 11, embodies certain additional features and modifications over that previously described, and will now be set forth in detail.

30 The members 84, 87, 88, 89, 90 and 91 have been previously mentioned, but instead of the casting 85 there is now substituted a casting 168, which is pivotally connected by a yoke 169 to the tractor A, and this yoke 35 has a screw 170, regulated by a hand wheel 171, whereby the front ends of the draw bars 84 may be adjusted vertically, as may be desired.

35 The lower portion of the casting 168 is provided with two sets of perforations 172 and 173, which adjustably accommodate the pins 174 and 175 of a yoke 176 and a frame 177 of a scarifier. The yoke 176 is rigidly secured to a hollow shaft or pipe 178, by bolts 179, and the shaft in turn is journaled in the frame 177, so that the line of draft and the rotated position of the shaft 178 may be readily adjusted by replacing the pins 174, 175 to the perforations 172, 173, 45 as may be required by the nature of the work to be done. The scarifier teeth or implements 180 are secured to the pipe 178 by bolts 181, and the vertical adjustment of the scarifier as well as its horizontal stability is affected by a pair of adjustable bolts 182, secured at their upper ends to the frame bars 84. The teeth 180 consist of wedge shaped castings having renewable triangular edged plates 180^a secured to their bottom faces so that the hard surface of the road may be readily plowed up and disintegrated.

50 A bar 183 is mounted in the vertical flanges of the draw bars 84 and to it are pivotally connected the front ends of a pair 60 of substantially L-shaped auxiliary draft

beams 184, to the lower ends of which is adjustably secured a smoothing board 185. Rearwardly of the board 185 is a heavy roller 186, which is connected to the beams 184 by suitable means such as links 187. The 70 members 184-185 are yieldingly pressed downwardly by springs 188, which are mounted on bolts 189 of the beams, and spread the lower ends of the bolts downwardly away from rearwardly extending 75 brackets 190, secured on the transverse beam 87.

The main structure and the various modifications as above shown and described illustrate some of the practical embodiments 80 of our invention. It is understood, however, that further modifications in the general design and structural details may be resorted to, provided the same are within the scope of the appended claims. Having now illustrated and described certain preferred embodiments of the invention, what we claim is:

1. The combination with a normal tractor having its forecarriage removed, of an 90 auxiliary frame extending forwardly to the front end of the tractor so as to support it, said frame having its rear end extended rearwardly of the tractor, a steering truck 95 at the rear end of the frame, and a road working implement adjustably suspended under the rear portion of the frame and arranged to be drawn by the tractor.

2. The combination with a normal tractor having a main frame, traction wheels 100 and a power member, and having its usual fore carriage removed; of an auxiliary frame extending rearwardly from the tractor and secured to its main frame so as to support it in an operative position when said fore carriage is removed, a steering carriage supporting the rear end of said auxiliary frame means for steering the carriage, and an earth working implement adjustably suspended under the auxiliary 110 frame.

3. The combination with a normal tractor having rear traction wheels and having its forecarriage removed, of a frame rigidly secured to and extending rearwardly from the unit so as to support its front end from whence said forecarriage has been removed, means for supporting the rear end of the frame, an implement arranged to be drawn by the traction unit, and means for adjustably connecting the implement to the frame.

4. The combination with a tractor unit having a main frame and rear drive wheels and having a driver's support, of a second frame secured to and extending rearwardly from the traction unit, an implement suspended from and under the frame, and means, operable from the driver's support, for adjusting the implement with respect to the frame.

5. The combination with a vehicle having front and rear supporting wheels, of a transversely tilttable axle connecting the rear wheels, a transversely tilttable implement arranged forwardly of the rear wheels, and means connecting the said axle with the implement whereby a tilting movement of the former will correspondingly tilt the latter.
- 10 6. The combination with a vehicle having front and rear supporting wheels, of a transversely tilttable axle connecting the rear wheels, a transversely tilttable implement arranged forwardly of the rear wheels, means connecting the said axle with the implement whereby a tilting movement of the former will correspondingly tilt the latter, and manually controlled means for tilting the implement independently of the first mentioned means.
- 15 7. A machine of the character described consisting of a frame, traction means at the forward end of the frame, a carriage tiltably connected to and supporting the rear end 25 of the frame, an implement arranged under the frame, and connected to the traction means, and means associated with the carriage for controlling the transverse angular position of the implement.
- 30 8. The combination with a tilttable road working implement supported by a frame and adapted to be drawn therewith over the road, of a carriage arranged rearwardly of the implement and tiltably connected to the frame, and means associated with the carriage for tilting the implement.
- 35 9. The combination with a tilttable road working implement supported by a vehicle frame and adapted to be drawn therewith over a road, of a carriage arranged rearwardly of the implement and tiltably supporting the frame, means mounted on the frame and associated with the carriage for automatically and correspondingly tilting the implement with respect to the carriage, and means for manually controlling the tilttable position of the implement irrespective of the position of the carriage.
- 40 10. The combination with a road machine or the like having a transversely tilttable earth working blade, of means associated with the blade, and engageable with the earth surface traversed by the blade, to automatically retain the blade in a parallel position with respect to the earth surface thus traversed, as the entire machine moves forward, said means including a carriage tiltably supporting the rear end of the machine.
- 45 11. The combination of a transversely tilttable earth engaging member adapted to be drawn over the ground by a tractor unit arranged in advance thereof, means associated with the member and engageable with the ground surface rearwardly of the member, to constantly retain a predetermined pitch
- or transverse inclination of the member as it travels over the ground, and manually controlled means operable from the tractor unit for adjusting said predetermined pitch.
- 50 12. The combination in a machine of the character described, of a frame, traction means at the front end of the frame, steering means at the rear end of the frame and including a transverse tilttable axle, an implement adjustably suspended under the frame and adapted to be drawn therewith by the traction means, and an adjusting mechanism connected with the said axle of the steering means.
- 55 13. The combination with a vehicle having a frame, of a carriage tiltably secured to and supporting the rear end of the frame, a fore carriage rigidly secured to the front end of the frame, an implement adjustably secured under the frame, and an adjusting mechanism controlled by the first mentioned carriage for adjusting the implement.
- 60 14. The combination in a machine of the character described, of a traction unit, a frame extending rearwardly therefrom and secured in rigid alignment therewith, a steering carriage supporting the rear end of the frame and adapted to be controlled from the traction unit, an implement adjustably suspended under the frame to be drawn therewith by the traction unit, and an adjusting mechanism controlled from the traction unit for adjusting the implement.
- 65 15. An attachment for a tractor comprising a frame extending rearwardly from the tractor and arranged to support the front end thereof from whence the usual steering carriage is removed, a steering carriage supporting the rear end of the frame, an implement adjustably carried by the frame rearwardly of the tractor, and controls extending from the rearwardly arranged steering carriage to the tractor whereby the operator of the tractor may steer said carriage.
- 70 16. The combination with a tractor having traction wheels supporting its rear end so that substantially the entire weight of the tractor is carried in advance of the axes of said wheels, an auxiliary frame detachably secured longitudinally of the tractor and extending rearwardly therefrom so as to support and counterbalance the front end of the tractor, steering means for supporting the rear end of the frame, and an implement adjustably arranged under the frame and arranged to be drawn by the tractor.
- 75 17. The combination with a tractor having traction wheels supporting its rear end, an auxiliary frame secured longitudinally of the tractor and extending rearwardly therefrom so as to support and counterbalance the front end of the tractor, steering means for supporting the rear end of the frame, a working unit arranged rearwardly of the tractor and connected with the draw bar

thereof, and means for vertically adjusting either side of the working unit with respect to the frame.

18. A machine of the character described consisting in combination, of a tractor having a main frame and supported at its rear on traction wheels, a second frame extending rearwardly from the tractor and having a wheeled support at its rear end, means for supporting the front end of the tractor from the second frame, an earth working implement drawn by the tractor and adjustably associated with the second frame, and means for steering the machine.

19. The combination with a normal tractor having rear traction wheels and having its normal steering carriage removed, of a frame secured to the tractor so as to support its front end from whence the steering carriage has been removed, a steering carriage supporting the rear end of the frame, an implement adjustably associated with the frame and adapted to be drawn therewith by the tractor, and means for operatively connecting the normal steering mechanism of the tractor with said steering carriage.

20. A machine of the character described consisting in combination, of a tractor supported at its rear on traction wheels, an auxiliary frame extending rearwardly from the tractor and having a wheeled support at its rear end, means for supporting the front end of the tractor from the auxiliary frame, an earth working implement drawn by the tractor and adjustably associated with the frame, an operator's support on the machine, and means, within reach of the operator for controlling the tractor, adjusting the earth working implement, and steering the machine.

21. The combination in a self-propelled road machine, of a traction unit having laterally spaced traction wheels, a frame extending rearwardly from the traction unit and having its front end carried thereby, supporting means for the rear end of the frame, said supporting means being transversely tiltable with respect to the traction wheels, a grader blade arranged under the frame to be drawn therewith and associated with the supporting means so as to be transversely tiltable therewith and with respect to the traction wheels, means for steering the machine, and means for manually adjusting the transverse inclination of the grader blade.

22. In a self-propelled road machine, a frame, a traction unit supporting the front end of the frame, a carriage for supporting the rear end of the frame, said carriage being transversely tiltable with respect to the traction unit, a second frame arranged below the main frame and rearwardly of the traction unit, a transversely arranged cutting blade carried by the second frame, a driver's

support on the machine, and controls extending to the driver's support for steering the machine and for adjusting the transverse inclination of the cutting blade.

23. In a self-propelled road machine, a frame, a traction unit supporting the front end of the frame, a carriage for supporting the rear end of the frame, said carriage being transversely tiltable with respect to the traction unit, a second frame arranged below the main frame and rearwardly of the traction unit, a cutting blade adjustably carried by the second frame, and means for vertically adjusting either or both ends of the cutting blade.

24. In a self-propelled road machine, the combination including a main frame, a traction unit supporting the front end of the frame, a steering carriage comprising a pair of laterally spaced wheels for supporting the rear end of the frame, a cutting blade arranged below the main frame and rearwardly of the traction unit, said cutting blade being associated with the steering carriage so as to be transversely tiltable therewith with respect to the traction unit.

25. In a self-propelled road machine, the combination including a main frame, a traction unit supporting the front end of the frame, a carriage for supporting the rear end of the frame and being transversely tiltable with respect to the traction unit, a second frame suspended under the main frame and rearwardly of the traction unit so as to be drawn thereby, a cutting blade carried by the second frame, and means for manually adjusting the transverse inclination of the cutting blade.

26. In a self-propelled road machine, a traction unit, a frame extending rearwardly from the traction unit and having its front end carried thereby, a cutting blade suspended transversely below the frame and rearwardly of the traction unit so as to be drawn together with the frame thereby, a carriage for supporting the rear end of the frame and adapted to travel on the earth surface traversed by the cutting blade, and means controlled by the carriage to automatically retain the cutting edge of the blade in a parallel position with respect to the earth surface thus traversed.

27. In a self-propelled road machine, a traction unit, a frame extending rearwardly from the traction unit and having its front end carried thereby, a cutting blade suspended transversely below the frame and rearwardly of the traction unit so as to be drawn thereby, a carriage for supporting the rear end of the frame and adapted to travel on the earth surface traversed by the cutting blade, means controlled by the carriage to automatically retain the cutting edge of the blade in a parallel position with respect to the earth traversed by the blade,

and means for manually adjusting the transverse inclination of the blade.

28. In a self-propelled road machine, the combination including a traction unit having a power element carried thereon and laterally spaced traction members driven thereby by the power element, a frame extending rearwardly of the traction unit and having its fore end carried thereby, a carriage supporting the rear end of the frame, said carriage being transversely tilttable with respect to the traction unit, a second frame suspended below the first mentioned frame,

and adapted to be drawn therewith behind and by the traction unit, a grader blade carried by the second frame and adapted to be angularly adjusted with respect to the longitudinal axis of the machine, an operator's station on the machine, controls extending to said station for adjusting the inclination of the cutting edge of the grader blade, and means for steering the machine.

In testimony whereof we affix our signatures.
